RING TAB FOR A TEAR STRIP OPENER

Francis M. Silver, Dayton, Ohio, assignor, by mesne assignments, to Ermal C. Fraze, Dayton, Ohio

Filed Mar. 23, 1967, Ser. No. 6,345

Term of patent 14 years

(Cl. D58—26)

FIG. 1 is a top plan view of a ring tab for a tear strip opener showing my new design;

FIG. 2 is a bottom plan view thereof;

FIG. 3 is an end elevational view thereof taken from the bottom of FIG. 1;

FIG. 4 is an end elevational view thereof taken from the top of FIG. 1; and

FIG. 5 is a side elevational view thereof.

I claim:

The ornamental design for a ring tab for a tear strip opener, substantially as shown.
